[57] CLAIM

The ornamental design for a rim seal for a can, as shown and described.

DESCRIPTION

FIG. 1 is a perspective view of a rim seal for a can showing my new design;

FIG. 2 is a side elevational view thereof, all sides being identical;

FIG. 3 is a bottom plan view thereof;

FIG. 4 is a fragmentary sectional view thereof, taken in the direction of the arrows along line 4—4 of FIG. 1.

FIG. 1

FIG. 2

FIG. 3

FIG. 4
